FENCE POST

Elza C. Barnes, Attica, Ind.

Continuation of application Serial No. 428,431,
January 27, 1942. This application May 6, 1943,
Serial No. 485,845

1 Claim. (Cl. 256—58)

This application is a continuation of applicant's pending application, Serial No. 428,431, filed January 27, 1942, now to be abandoned.

This invention relates to a fence post of the metal type having a plurality of tongues extending from the fence side of the post. The gist of the invention resides in the arrangement of the tongues on the fence post wherein there is a pair of tongues for each fence wire, one tongue laterally spaced from the other tongue along the wire with one tongue turned downwardly and the other tongue turned upwardly, and this arrangement of tongues in each pair reversed for each alternate wire of the fence whereby the alternate pair has the corresponding tongues therein reversed in direction.

The arrangement of the tongues in this manner makes a locking system on the post without use of any additional fastening elements and without bending the tongues or deforming them in any manner. The invention provides a structure which securely holds each individual fence wire in line and position on the post without any twisting or kinking of the line wires, and at the same time allows for individual contraction and expansion of the line wires along the post, the pair of tongues for each line wire furnishing a smooth bearing of appreciable area for the line wire passing thereacross. Nothing is bent onto the line wire or clamped thereto that will in any manner tend to wear or cut the line wire, particularly the coating thereof, under movement thereof due to changes in temperature producing a contraction or expansion, wind pressure, or even the extreme condition when some one attempts to climb the fence.

A further advantage of the invention resides in the fact that by reason of the arrangement of the tongues on the post, there is no tendency to pull the post in either direction along the fence so that the post will remain in its vertical position as originally driven into the ground. Each and every line wire of the fence remains under the tension as originally produced upon stretching the fence so that no one wire may have a different tension between one post and the next post than another wire, and further, by reason of the manner of attachment of the various line wires to a single post, no one wire is secured to that post with any greater degree of tightness than another wire.

Furthermore, the invention permits easy and quick erection of the fence and attachment to the various posts therealong without any elaborate tools or the like, and in addition, permits

easy and quick removal of the fence from the post without any damage being done to either the post or the fence, permitting reuse again of both the posts and the fence. This is of prime importance, particularly under present war time conditions when fence wire is not available and change in location of fencing is required on farms to meet important seasonal conditions.

These and many other objects and advantages 10 of the invention will become apparent to those versed in the art in the following description of one particular form as illustrated in the accompanying drawing, in which

Fig. 1 is a view in front perspective of a post 15 embodying the invention;

Fig. 2, a view in front elevation of the upper portion of a post embodying the invention and illustrating the application of a fence thereto; and

Fig. 3, a view in section on the line 3—3 in Fig. 2.

Like characters of reference indicate like parts in the several views in the drawing.

Any type of metal post may be employed providing it has means for carrying tongues in laterally spaced apart relation on its fence side. In the present showing a T-type post, generally designated by the numeral 10, is illustrated, wherein there is a flat fence side 11 and a central, reinforcing rib 12 rearwardly projecting therefrom. The post may have its lower end pointed in the usual manner to facilitate driving into the ground and will carry in most instances a bearing plate 13 to increase the bearing area of the post near the surface of the ground.

Beginning at the top of the post, on the fence side thereof, is a pair of outwardly projecting tongues 14 and 15. In the present form of the 40 invention, these tongues 14 and 15 are formed by punching and bending them from marginal portions of the face section 11 of the post. The tongue 14 is secured by its upper end to the face part of the post and slopes downwardly and forwardly therefrom while the tongue 15 is secured by its lower end to slope outwardly and upwardly from the face 11. As indicated, these tongues are generally rectangular in shape and are preferably provided with non-pointed outer ends.

Spaced downwardly from this pair of tongues 14 and 15 a distance equal to the desired spacing between the top wire, herein shown in the present instance as a barbed wire 16, and the next lower wire of the fence, shown as the top line wire 17 of a woven wire fence, is a second

pair of tongues 18 and 19. In this pair, the tongue 18 on the left-hand side of the post in vertical alignment with the tongue 14, is turned outwardly and upwardly, and the other tongue 19 in horizontal alignment therewith is turned downwardly and outwardly, this being the opposite arrangement from that of the corresponding tongues 14 and 15 in the next upper pair.

In like manner, pairs of tongues 20—21, 23—23, 24—25, 26—27, 28—29, 30—31, and 32—33, are provided along the post spaced apart in accordance with the spacings of the line wires of the fence, it being customary to have a closer spacing of these wires near the base of the fence. The number of pairs of these tongues will be sufficient in any event to take care of the highest fence desired for the particular length of post employed. It is to be kept in mind that each pair of tongues has the tongues therein turned in opposite directions in relation to the next tongues aligned therebelow.

The invention is particularly adapted for use in conjunction with the universally employed woven wire fences. Referring to Fig. 2, after the woven wire fence, generally designated by the numeral 35, has been attached to an end post (not shown) and stretched, it is initially hung on the individual line posts, one such line post 10 being indicated in Fig. 2. The top line wire 17 is hung over the upwardly extending tongue 18; the next line wire 34 is hung over the tongue 21 and in like manner the various line wires are hung over the upturned tongues throughout the length of the post. Then in order to complete the securing of the fence to the post, any suitable sort of a tool, such as a screw driver, a flat bar, or even a round bar 36 as indicated in Fig. 2, is inserted under the straight edge of the tongue 19 and over the top of the line wire 17 to pull the wire 17 down and allow it to snap back under the tongue 19. The lengths and outwardly extending angles of slopes of the tongues 18 and 19 are made to be such that the line wire 17 is permitted to extend on across the post 10 over the tongue 18 and under the tongue 19 in firm contact therewith but without kinking or bending of the wire. The line wires of the fence 35 are initially provided with bends or kinks 37 to allow for contraction of those wires in cold weather, and these kinks are not straightened out when the line wires are interengaged between the tongues on the post so that the line wires are still free to contract and expand in the usual intended manner. In the showing of Fig. 2, these kinks happen to fall between the horizontally disposed tongues of the post 10, but they may come at any position along the line wires in reference to the post 10. In like manner, each of the line wires of the fence 35 are interengaged between the downwardly turned tongues of each of the various pairs until all of the line wires of the fence are thus secured behind the tongues, one tongue being turned downwardly and the other tongue being turned upwardly in each pair over the respective line wire, with the tongues turned in opposite directions from the next adjacent line wire.

This opposite turning of the tongues is of extreme importance, as above indicated. For example, referring to the two uppermost line wires 17 and 34 of the fence 35, the upper wire 17 bears downwardly against the flat surface of the tongue 18 to have line contact thereacross while the wire 34 bears along the flat surface of the upturned

tongue 21 on the right-hand edge of the post 10. By reason of the interconnecting stay wires 38 and 39 between the two line wires 17 and 34, the line wire 34 is held in engagement under the tongue 20 by the wire 38 and the wire 17 is held upwardly under the tongue 19 by the wire 39. In other words, disengagement from the tongues is tended to be prevented by reason of the cooperation of the vertical stay wires of the fence itself.

Where it is desired to change the location of the fence from one field to another, the same instrument, such as the rod 36, may be engaged under the outer straight edge of a tongue and carried over or under the corresponding line wires as the case may be, to pry that line wire out from under the selected tongue until the line wires are all removed from the series of tongues turned in one corresponding direction. Then the fence may be lifted out of the other set of tongues to free the post from engagement with the fence. This is of particular advantage when one or more posts only may want to be removed or replaced. The entire fence may be loosened from one end to permit slack in the fence to facilitate removal from the individual posts. It is to be noted that by reason of the alignment of the tongues in each of the several pairs thereof, the line wires may slide across these tongues individually without tending to pull the post therealong. Likewise the post itself, should it be struck by some implement tending to push it along the fence, will resist leaning therealong by reason of the oppositely opposed tongues in respect to the various pairs. For example, should the post 10 be tended to be pushed to the left by its top end to rock it in the ground, the tongue 20 would bear down against the wire 34 from the top side and the tongue 21 will bear upwardly thereagainst from the under side and so on throughout the alternate pairs of tongues tending to resist that movement of the post. The alternate pairs of tongues would resist shifting of the post angularly in the right-hand direction. As indicated, the structure lends itself very well to the usual mounting of the barbed wire 16 in spaced relation above the top of the woven wire fence 35. No separate fastening elements are required even for the barbed wire since it may be sprung under the tongue 14 after being placed across the tongue 15.

It is therefore to be seen that I have provided a very simple structure readily lending itself to high and quick production without complicated tools, and a structure wherein there is but the one integral post without requirement of additional securing or fastening elements separate from the post. The securing tongues are spaced apart a substantial horizontal distance by being presented along each edge of the face of the post and each of the tongues has a considerable lateral area providing sufficient length of contact with the individual wires to prevent cutting or biting therein.

While I have herein shown and described my invention in the one particular form, it is obvious that structural variations may be employed without departing from the spirit of the invention and I therefore do not desire to be limited to that precise form beyond the limitations as may be imposed by the following claim.

I claim:
A metallic fence post for detachably carrying a wire fence comprising a substantially flat fence side face; a reinforcing rib extending longitudi-

nally of the reverse side of the post and substantially centrally thereof to form a T iron; said post having a plurality of substantially rectangular notches therethrough, spaced apart along, and open from the vertical edges of said flat face, and positioned in pairs, one notch opposite the other in horizontal alignment as to top and bottom margins; and a substantially rectangular metal tongue extending diagonally upwardly and outwardly in fixed position from said flat face from the lower marginal edge of each of the said notches along one of said post edges; and a like tongue extending diagonally downwardly and

5 outwardly in fixed position from said flat face from the upper marginal edge of each of the said notches along the other edge of said post; said notches and said tongue being so dimensioned that a line wire of said fence may bear against said flat face and may rest over and be in sliding contact with an upturned tongue at one side of the post and under and in sliding contact with a downturned tongue on the other side of the post, a post marginal edge opening being provided by 10 said notches under each of said tongues.

ELZA C. BARNES.
